Lacy & Lacy
ATTORNEYS

UNITED STATES PATENT OFFICE.

HANS H. PETERSEN, OF CORRECTIONVILLE, IOWA.

LOADER.

1,426,212.

Specification of Letters Patent. Patented Aug. 15, 1922.

Application filed October 14, 1920. Serial No. 416,787.

To all whom it may concern:

Be it known that I, HANS H. PETERSEN, a citizen of the United States, residing at Correctionville, in the county of Woodbury 5 and State of Iowa, have invented certain new and useful Improvements in Loaders, of which the following is a specification.

This invention relates to means for transferring manure from a barn yard to a wagon 10 for transportation to a field which is to be fertilized and the object of the invention is to provide a strong, compact, simply constructed and easily operated mechanism which will efficiently load the manure into 15 the waiting conveyance.

The invention is illustrated in the accompanying drawings and will be hereinafter fully set forth.

In the drawings—

20 Figure 1 is a view partly in side elevation and partly in longitudinal section of a loader embodying my improvements;

Fig. 2 is a detail plan view of a part of the operating mechanism;

25 Fig. 3 is a plan view of the loader;

Fig. 4 is an end elevation of the loader;

Fig. 5 is a detail transverse section on the line 5—5 of Fig. 1.

30 Fig. 6 is a detail elevation of the upper end of the conveyer, viewed from the side opposite that seen in Figure 1.

In carrying out my invention, I employ a base or main frame comprising sills 1 which may be of any substantial form and 35 are connected at one end by an end plate 2 and near their opposite ends by transverse beams 3. The said beams 3 project beyond one sill 1 and the extended ends of the beams are connected by a bar 4. The driving mech- 40 anism is supported upon these beams 3 and bar 4 as will be presently more fully set forth. Upon the sills 1, I secure an upper frame consisting of side bars 6 which extend from that end of the base at which the 45 plate 2 is located to a point adjacent the center of the base and serve to support platforms 7 which bridge the said side bars, as clearly shown. These platforms are separated or spaced apart longitudinally of the 50 side bars so as to provide a feed opening 8 through which the manure may be deposited upon the conveyer, and resting against the side bars are inclined ways 9 up which a scoop may be drawn so as to discharge 55 through the opening or space 8 as will be readily understood. It will also be under-

stood that when scoops are employed draft chains or cables will be attached to the same and extended across the base frame to be coupled to draft animals so that the scoop 60 will be readily drawn up the way 9 at one side of the platform and discharged onto the conveyer. It may sometimes be convenient and more desirable to load the fertilizer onto the conveyer by merely shoveling 65 or pitching it through the opening 8. Where the accumulation of manure is extensive, it is possible to locate the base or main frame immediately adjacent the pile of material which may then be quickly fed 70 through the opening 8 by the use of pitch forks or shovels as is obvious. It may sometimes also be more convenient and economical to feed the material onto the conveyer by the use of barrows or similar receptacles 75 which may be readily moved up the inclined ways 9. It will thus be seen that I do not limit myself to any particular manner of delivering the material into the loader and it is also to be understood that while the 80 apparatus is intended primarily for loading manure into farm wagons, as previously stated, it may be advantageously used for handling other materials. It is also to be understood that the apparatus may be em- 85 ployed in connection with a portable engine to spread over a field fertilizer delivered onto the conveyer by wagons.

Adjacent the inner ends of the side bars 6, inclined side bars 10 are secured upon the 90 sills 1 and the upper ends of these side bars are supported and braced by standards 11 rising from the sills or from the beams 3 as may be most convenient and as will be readily understood. Extending along the 95 inner sides of the bars 10 and the sills 1 are strips 12 on which are mounted rollers 13 to support the conveyer consisting of trans- 100 verse bars or slats 14 connected by parallel endless chains 15 as will be readily under- 105 stood. At the inner ends of the bars 6, guide rollers 16 are mounted to bear upon the upper surfaces of the bars or slats 14 at the ends of the same and thereby prevent the upper run of the conveyer rising abruptly 110 so as to wear against the under side of the platform and also to insure a horizontal surface of the conveyer below the feed opening as will be readily understood on reference to Fig. 1. The conveyer is supported 110 by a drum or roller 17 mounted in and ex- tending between the sills 1 immediately ad-

jacent the end plate 2 and a second drum or roller carried by a shaft 18 mounted in suitable bearings at the upper ends of the inclined side bars 10. A supporting roller or 5 drum 19 may be mounted upon the braces 11 to support the under run of the conveyer and prevent excessive sagging of the same.

Upon one end of the shaft 18, I secure a sprocket 20 around which is trained a chain 10 21 which also passes around a sprocket 22 upon a shaft 23 which is mounted upon the frame provided by the beams 3 and the bar 4. The sprocket 22 is loose upon the shaft and a bearing sleeve 24 is fitted upon 15 the said shaft inwardly from the sprocket and supports the inner end of a driving shaft 25 which extends forwardly and is journaled upon the outer beam 3, the outer or forward end of the said shaft carrying 20 a band pulley or driving gear wheel 26 to which power is applied from any convenient or preferred motor. It will, of course, be understood that power may be applied directly to the shaft 23 and the band pulley 25 or wheel 26 utilized as a fly wheel, and it will also be understood that instead of a mechanical motor the power may be derived from a draft animal driven source. Upon the shaft 25, a pinion 27 is adjustably 30 secured and adapted to mesh with a gear 28 which is keyed to the shaft 23, as indicated at 29. The pinion 27 may be adjusted longitudinally of the shaft 25 and radially of the gear 28 so that the speed of rotation 35 of the shaft 23 may be varied to suit the requirements of any particular work and the pinion 27 will be secured in a set position by a set screw mounted in its hub and bearing upon the shaft 25 as will be readily 40 understood. The gear 28 may be a multiple gear or may be one of a plurality of interchangeable gears of various diameters. The hub of the sprocket 22 is provided with an annular groove, as indicated, and this 45 groove is engaged by a pin or roller upon a lever 31 which is fulcrumed upon the front beam 3 and is provided with a latch 32 adapted to engage a rack 33 on the beam so that the lever will be held in a set position. The hub is adapted to engage a clutch 50 collar 30 secured to the shaft 23 so that it may be thrown into or out of gear as is obvious.

In the use of the device, the pinion 27 55 is adjusted relative to the gear 28 so that the conveyer will be driven at the desired speed and the material to be loaded is fed continuously through the feed opening 8 so as to drop directly onto the conveyer 60 which will carry it up and over the wagon stationed under the high end of the conveyer so that as the conveyer passes around the upper drum or roller the material will be discharged into the wagon. When one 65 wagon has been loaded, it is not necessary

to stop the engine while another wagon is being brought into position to be loaded inasmuch as shifting of the lever 31 will quickly disengage the members of the driving gearing and thereby stop the travel of 70 the conveyer. Wear upon the parts of the conveyer will thus be avoided while the time required to drive a loaded wagon out of position and to bring an unloaded wagon into position to be loaded is so short that 75 there would be no economy in stopping the engine. It will be readily noted that the driving gearing is all located below the conveyer and under the inclined portion of the same so that the conveyer will serve as 80 a cover for the driving gearing to prevent choking of the same by the material being handled. The apparatus is exceedingly simple in the construction and arrangement of its parts and may be easily operated. 85 The parts are compactly arranged so that they are not apt to get out of order and they may be manufactured at a low cost. It will be noted that my apparatus operates continuously so that the material to be loaded 90 will be supplied to the wagon in a continuous stream and it is not necessary to intermittently or periodically stop the operation to permit a sufficient deposit to be placed upon the conveyer. It will also be noted 95 that the platforms 7 upon the base cover the lower conveyer supporting drum or roller and also cover the guide rollers 16 so that the material fed onto the conveyer cannot drop upon these elements and choke the 100 operation of the same.

The driving chain 21 passes over an idler 34 which is carried by a bracket 35 adjustably secured to the adjacent standard 11 whereby the chain is supported against and held out of the way of vehicles driving under the delivery end of the conveyer. The chain may also by this device be kept under the proper working tension.

Mounted for pivotal movement about the 110 shaft 18, at the outer sides of the side bars 10, are arms 36 and journaled in the lower ends of these arms beyond the side bars is a spreader shaft 37. Blades 38 radiate from the spreader shaft and extend along the 115 same between the arms 36 so that when the spreader is properly adjusted, the material discharging over the upper end of the conveyer will be received by the revolving blades and by them will be thrown forward 120 from the conveyer a greater or less distance according to the adjustment of the spreader arms 36. To rotate the spreader shaft, a sprocket pinion 39 is secured on the shaft and a chain 40 is trained around the same 125 and a sprocket gear 41 on the shaft 18, the described gearing being located at that side of the apparatus remote from the sprocket 20. To adjust the arms 36 out of the path 130 of the material or more or less into said

path, I provide a hand lever 42 which is fulcrumed upon a side bar 10 and to which is pivoted a bail 43, the side members of the bail extending through clips 44 on the arms 36. The weight of the spreader blades and shaft with the sprocket 39 tends to hold the arms in a vertical position with the spreader below the conveyer out of the path of the material. By swinging the lever 42 rearwardly, however, the engagement of the sides of the bail with the ends of the clips will cause the arms 36 to swing toward a position in alinement with the side bars 10 so that the spreader blades will act on the material and throw it forward in the wagon or other conveyance. I am thus enabled to distribute the load evenly in the wagon.

Having thus described the invention, what is claimed as new is:

1. In a loader, the combination of a conveyer having an inclined portion, spreader arms pivotally mounted at the upper end of the inclined portion of the conveyer, a

spreader shaft mounted in the outer ends of said arms, radial blades extending along the shaft between the arms, means for rotating the shaft, and means for pivotally adjusting the arms, the arms being normally so disposed that the spreader shaft is below the end of the conveyer.

2. In a loader, the combination of a conveyer having an inclined portion, spreader arms pivotally mounted at the upper extremity of the inclined portion of the conveyer, a spreader carried by the ends of said arms and thereby disposed beyond the end of the conveyer, means for operating the conveyer and simultaneously operating the spreader, clips on the sides of the spreader arms at the ends thereof remote from the spreader, a bail bridging the spreader arms and engaging said clips, and an adjusting lever mounted upon the conveyer and pivotally connected with said bail.

In testimony whereof I affix my signature.

HANS H. PETERSEN. [L. S.]
